DEVICE FOR USE IN FILLING CAVITIES
IN TEETH

Hillard M. Holmes, Lake Tahoe, Calif.

Application January 12, 1951, Serial No. 205,671

6 Claims. (Cl. 32—60)

1

This invention relates to a method of filling cavities in teeth and to a device for use in filling such cavities.

A recent filling material in dentistry identified in the dental profession as plastic acrylic filling, being an acrylic plastic that is impervious to any of the natural fluids of the mouth and that more nearly correspond to natural tooth color and color texture than any material heretofore discovered and used in dentistry.

Up to the present time a large percentage of the fillings of the above-described material placed in the patients' teeth have proven to be failures for the reason that they have become leaky or have loosened entirely from the tooth cavities.

One of the objects of the present invention is the provision of a method of filling cavities with a setting plastic material of the above type or of any type having the same characteristics so that said fillings will not become leaky or loosened.

Another object of the invention is the provision of a device for use in carrying out the above-mentioned method.

A still further object of the invention is the provision of a method and means for procuring substantially perfect marginal adaptation of the plastic filling on all portions of the cavity margins simultaneously.

An additional object is the provision of means for forcing the setting plastic filling material in a plastic state into every minute crevice and undercut of the cavity under a uniform pressure and maintaining said pressure until the filling material has set.

It should be mentioned that the use of acrylic plastic filling material is principally in those cavities that are in the outer sides or between the front teeth in the mouth, and which fillings would be unsightly or objectionable to most persons if of silver amalgam or gold. In other words, the said plastic filling material is used where it is important that the filling match the color and color texture of the tooth that is filled therewith so that the filling will not be noticeable as a filling although visible during the normal facial movements of the person when talking, laughing or eating.

Other objects and advantages will appear in the description and in the drawings.

In the drawings.

Fig. 1 is an exploded part sectional and part elevational view of the various elements of the device for use in filling a tooth, a tooth being indicated at the left hand end (looking at the drawing) in which the cavity to be filled is shown.

2

Fig. 2 is a still larger view than that of Fig. 1 in which the device of Fig. 1 is assembled and in tooth filling position with the filling material shown in the cavity and in the device.

5 Fig. 3 is a plan view of a matrix adapted for use with the device shown in Fig. 1.

Fig. 4 is a plan view of a slightly different matrix than in Fig. 1, the same elements being in each matrix, but the filling element or tube of Fig. 4 being at a different angular position relative to the matrix sheet.

Figs. 5, 6 are respectively edge or side elevational views of the matrices of Figs. 3 and 4.

15 Fig. 7 is a front elevational view of a tooth to be filled illustrating a matrix of the type shown in Fig. 3, but trimmed and fitted over the cavity preparatory to sealing the same to the tooth.

10 Fig. 8 is an enlarged fragmentary sectional view of slightly different shaped filling elements or members respectively on the matrix and filling device than is shown in the other figures.

20 Fig. 9 is a sectional view of a modified form of the invention that is more compact than the other devices.

25 It is to be understood that the devices shown in all of the views are greatly enlarged over their actual sizes, and the parts shown in Fig. 2 are substantially enlarged over that shown in Fig. 1.

In the drawings (Figs. 1 and 2), the tooth to be filled is indicated at 1 and a cavity 2 formed therein. For purpose of explanation of the invention the same number may be given the tooth in Fig. 7 that is to be filled, and the cavity in said tooth is shown as being adjacent to the next tooth 3.

30 Cavity 2 may be prepared for filling in the usual manner, having undercut sides to retain the filling material.

In Figs. 3 to 6 inclusive are shown several matrices, the body of each being the conventional material of thin readily bendable metal. Sometimes this metal is slightly tempered to more readily retain its bent shape, and at other times it is more in the nature of a foil that is easily bent and that has little if any springy characteristic. Such material as is used at the present time for the same general purpose is suitable for use.

The matrix of Figs. 3 and 5 is thin sheet metal body 4 that is oblong in shape and centrally apertured with a filling tube 5 secured in the aperture at one end and projecting from said body at right angles to the plane of said body.

45 In the matrix of Figs. 4 and 6, the body 1 has a filling tube 8 secured thereto at an angle less

than 90 degrees. Otherwise the two matrices are the same.

The matrix of Figs. 3 and 5 are used where the cavity is so positioned that the tube 5 will be exposed and directed generally toward the center of the opening of the mouth when the matrix is in position, whereas the matrix of Figs. 4 and 6 are used when the cavity is where the tube 8 will be directed generally toward the center of the mouth opening when the mouth of the patient is open. The reason for this is that the filling device that is to be attached to the tubes 5 or 8 (as will later be explained) will project from the tube to which it is attached, and will usually project from the mouth. Hence it is more convenient for both the dentist and the patient if it projects from the mouth without the necessity for uncomfortably distorting the mouth.

The rectangular shape of the matrices shown in Figs. 3 to 6 inclusive is common, inasmuch as this provides ample material for trimming and shaping the matrix around the tooth and over the cavity to be filled. In Fig. 7 the matrix 6 has been trimmed so that the edges are curved, and the upper edge will extend along or across the gum line. The tube 5 or 8 in any event communicates directly with the open side of the cavity to be filled.

After the body of the matrix has been trimmed and shaped so that it will fit over the cavity to be filled, as explained above, it may be secured in place by use of a sealing wax 6 such as a conventional impression compound. This wax or compound may extend completely over the matrix and the portion of the tooth around the matrix and adheres firmly to the tooth and to the matrix. Obviously it may extend over adjoining teeth in some instances. However, the wax does not absolutely seal off the cavity in a manner preventing escape of air. Usually such escape is possible at the gum line inasmuch as most cavities in the front teeth occur close to such line. If not, a fractional portion of the matrix at a point along its edge may be left uncovered to permit escape of air from within the cavity.

The matrix over the cavity is shaped so that the curvature of its inner surface where it extends across the cavity conforms to the normal curvature of that portion of the tooth in which the cavity is located, before such cavity was made. The maintenance of this curvature is quite important, particularly where the filling is between teeth. If it is not maintained, the surface of the filling will not have the normal and proper position relative to the surface of the adjoining tooth that is adjacent thereto, and trouble will develop.

Where the matrix is drawn tightly into engagement with the tooth to be filled, as has been the practice heretofore, the matrix usually flattens out slightly where it extends across the cavity. The exterior surface of the filling material takes this flattened form, with the result that it does not have the desired and highly important surface curvature it should have.

With the present invention the matrix is not tensioned, and there is nothing to change its curve. Once the desired curvature is procured, it will stay that way.

Where the cavity is between teeth or nearly so and the matrix must be positioned between the teeth in order to extend over the cavity, it

is customary to wedge the adjoining teeth apart a sufficient distance with a peg to insert the matrix. After the tooth is filled and the wedge or peg is withdrawn, the teeth will come together.

After the matrix is secured in position by the wax or compound, the filling device may be coupled with the filling tube 5 or 8.

This filling device comprises a cylindrical body 10 having a head 11 at one end thereof. The opposite end is open (Fig. 1). The head 11 is apertured for receiving one end of a discharge tube 12 that is secured to said head coaxial with the said aperture therein.

The tube 12 may be counterbored at its outer end as at 14 to closely receive the filling tube 5, and the diameters of the tubes 5, 12 are the same. Shoulder 15 defining the juncture between the counterbored portion 12 and the bore in the discharge tube may function as a stop for engagement with the outer end of tube 5 so that the bores in said tubes will be smooth and continuous as seen in Fig. 2.

Reciprocably fitted in the open end of the body 10 is a plunger 16. This plunger may project outwardly of the open end of the body 10 and a hollow cap 17 receives the outwardly projecting end of the plunger therein. This cap 17 has a head 18 closing its outer end, and a helical spring 19 may be within said cap between head 18 and the end of the plunger when the cap is over an end of said plunger.

Secured to head 18 by any suitable means, such as a machine screw 20, is a generally U-shaped clip of spring material, generally designated 21. Legs 22 of clip 21 are of the same length and in substantially opposed relationship for extending longitudinally of the cap at opposite sides thereof. The closed end of the clip extends across the head 18 of the cap and the screw 20 extends through said closed end.

Said legs 22 are bowed longitudinally with their concavely curved sides facing each other, and their outer end portions at their free ends are turned inwardly toward each other, and slightly rearwardly to provide hooklike elements 23. These elements 23 are adapted to engage a side of an annular outwardly opening recess 24 that extends around the body 10 when the filling device is assembled.

Around the open end of cap 17 is a radially outwardly projecting flange 25 across which the legs 22 extend. The hooklike elements 23 on the free ends of legs 22 are spaced axially outwardly of the annular flange 25 a distance sufficient for said elements to engage the side of said recess 24 that is adjacent the cap 17, and to hold spring 19 under sufficient compression to provide the desired pressure on the filling material to be carried in body 10 between the end of plunger 16 and head 11 as will later be described more in detail.

The plastic material, as has already been stated is an acrylic resin and is indicated at 27 in Fig. 2. This plastic material is placed within the cylindrical body 10 in a plastic condition after the body 10 has been coupled to the filling tube 5 (or 8) of the matrix.

The coupling of the latter to the matrix filling tube usually is done after the matrix is secured over the cavity, but in any event the discharge tube 15 of the filling device may then be secured to the matrix generally as indicated in Fig. 2. The amount of sealing wax or impression compound that is used must be sufficient to firmly hold the matrix in position and to hold the filling device in position coupled to the matrix.

After the discharge tube 12 is firmly coupled to the tube 5 and is secured in position, the plunger 16 is forced against the filling material by moving cap 17 axially of the plunger to the position indicated in Fig. 2 when the hook or catches 23 will automatically snap into the recess or groove 24.

In the event the plunger fits snugly in cap 17, a vent hole 28 may be provided in the cap head to permit quick escape of air. Also a vent 26 may be made in side of cap 10. After passing vent 26 the speed of the piston will be checked before it reaches the plastic.

It is also to be noted that the hook-like elements 23 have slanted generally axially and inwardly facing surfaces 29 (Fig. 2) that initially engage the free end edges of the body 10 upon axial movement of cap 17 toward the body 10 to automatically spread the legs 22 so that said end elements 23 will snap into the recess 24 when they reach the latter.

The amount of plastic material with which the body 10 is originally charged should be slightly in excess of the amount required for the cavity and for filling the passageway between the cavity and said body 10, so that the pressure on the plastic material is applied over the full cross sectional area of the body 10 during setting and polymerisation of the plastic material.

The relatively large area of the end of plunger 16 relative to the area of the bore leading into the cavity through tube 12 and to the area of the cavity, together with the tension of spring 19 will create a uniform sustained pressure of about 80 lbs. per square millimeter on the filling material in the cavity. The pressure may be varied to suit conditions, and may be more or less than the above, but whatever pressure is employed it should be sufficient to effect substantially sufficient compression of the resilient dentine of the tooth to compensate for the shrinkage in the acrylic resin during setting of the latter so that the filling will be a tight fit in the cavity after the acrylic resin has set. Normally the above pressure, or substantially such pressure is adequate.

The maintenance of uniform pressure on the acrylic plastic will result in a uniformly dense filling as well as insuring a tight and satisfactory filling.

About ten minutes' time is adequate for the plastic material to set, after which period the tube 5 may be severed along line X—X (Fig. 2) and the body 10 may be replaced by a new one for another filling operation. The wax or compound 6 is readily removed, together with the matrix body 4, after which the surface of the filling may be sanded down and polished. The correct curve or contour has been kept on the filling inasmuch as the curvature of the body 1 has been correct, and no tension has been placed on said matrix as in a conventional operation where the matrix is drawn against the tooth around the cavity under tension.

To remove the cap 17 from the body, it is only necessary to press the legs toward each other at points between flange 25 and the closed end of the clip element, when the hook ends 23 will be caused to spring apart as the legs engage said flange.

During the setting period of the plastic, the filling device may be left in place coupled to the matrix. It need not be held by any other means than the matrix, being relatively small and light in weight.

The expendable portions, such as the matrix and the body 10 including the filling tubes is quite reasonable.

In Fig. 8 the filling tube that is on the matrix is designated 31 and is generally frusto-conical in shape with the larger diameter end connected with the matrix. The discharge tube 32 that is on the filling device is complementary to the filling tube 31 so as to receive the latter with its inner sides in tight engagement with the outer sides of tube 31. This structure is suitable where the larger diameter end of the filling tube is not larger than the open side of the cavity, and the wax or compound that extends over the tube 32 will have more holding strength than on the straight sides of tube 12.

In Fig. 9 a more compact filling device is provided for them in Fig. 2. In Fig. 9 the cylindrical body 34 in which the plastic charge is to be held is the same as in Fig. 1 except that it does not have the external groove 24 therein, and the discharge tube 35 may be threaded into the head 36 of said body 34.

The cap 37 has a flange 38 at its open end the same as cap 17, but the said cap telescopically fills over the body 34. The spring clip 39 is much the same as clip 21 of Fig. 1 except that the hook ends 40 are adapted to snap over the closed end of body 34.

Instead of the longer plunger of Fig. 1 a piston 41 is reciprocably filled in body 34, which piston may have a head at the end adjacent the head 36 of body 34, and the other end formed with an axially rearwardly opening recess in which spring 42 extends.

This spring is adapted to react between the piston head and a member 44 also reciprocable within body 34. An adjusting screw 45 threadedly extending through the head 46 of the cap, is adapted to regulate the tension on spring 42 when the ends 40 are engaged over the end of the body 34. Screw 45 may also extend through the closed end of the clip 39 and a lock nut 47 on said screw may not only lock the screw in adjusted position, but also clamp the clip 39 to cap 37. By recessing member 44 for the spring, the over all length of the filling material may be varied as desired and found necessary.

The cap is removed in exactly the same manner as in the case of cap 17. By pressing the legs of clip 39 toward each other between flange 38 and the closed end of the clip, the outer ends of said legs will spring apart. A vent may be in the head of cap 37 the same as in cap 17 to permit free escape of air from within the cap as it is slipped over the body 34.

I claim:

1. In apparatus for filling the cavity in a tooth with a setting plastic material, a matrix of thin sheet material adapted to be trimmed and shaped to fit over said cavity with marginal portions against the marginal portions of said tooth around the edges of said cavity, an inlet in said matrix and a passageway communicating with said inlet through which said plastic material in a plastic state is adapted to be forced for ejection into said cavity when said matrix is secured over the latter, and means connected with said matrix for supplying said material to said passageway for passage through the latter under pressure and means automatically operative for yieldably holding said material so injected into said cavity under uniform pressure during the setting period of said plastic.
2. In apparatus for filling the cavity in a tooth

with a setting plastic material, a matrix of thin sheet metal adapted to be trimmed and shaped to fit over said cavity and against said tooth, a cartridge for holding a supply of said material, a passageway communicating between the inside of said cartridge and the side of said matrix that is adapted to fit against said tooth for passage of said material from said cartridge into said cavity when said matrix is secured against said tooth, and means carried by said cartridge for moving said material through said passageway and means automatically operative for yieldably holding such material in said passageway and cavity under uniform pressure when said cavity is filled with material discharged from said passageway and when said matrix is secured against said tooth.

3. In apparatus for filling the cavity in a tooth with a setting plastic material, a matrix of thin sheet metal adapted to be trimmed and shaped to fit over said cavity and against said tooth, a cartridge for holding a supply of said material, a passageway communicating between the inside of said cartridge and the side of said matrix that is adapted to fit against said tooth for passage of said material from said cartridge into said cavity when said matrix is secured against said tooth, and means carried by said cartridge for moving said material through said passageway and means automatically operative for yieldably holding such material in said passageway and cavity under uniform pressure when said cavity is filled with material discharged from said passageway and when said matrix is secured against said tooth, said matrix being separable from said cartridge, and a quick detachable coupling releasably securing said matrix and said cartridge together.

4. An apparatus of the character described comprising: a cartridge holding a supply of a setting plastic material, a discharge outlet at one end of said cartridge adapted to be connected with the filling tube on a matrix, a piston within said cartridge movable toward said outlet and against such material when said cartridge has a charge of such material therein between said outlet and said piston, means for yieldably holding said piston against said plastic comprising a spring engaging the end of said piston opposite said plastic and an element releasably connected with a fixed point on said cartridge and said spring for holding said spring under compression against said piston.

5. An apparatus of the character described comprising: a cartridge holding a supply of a setting plastic material, a discharge outlet at one end of said cartridge adapted to be connected with the filling tube on a matrix, a piston within said cartridge movable toward said outlet and against such material when said cartridge has a charge of such material therein between said outlet and said piston, means for yieldably holding said piston against said plastic comprising a spring engaging the end of said piston opposite said plastic, spring arms releasably connected with said cartridge at opposite points thereon at one of their ends and a cross member connected with the opposite ends of said arms and over said spring for holding said spring under compression against said piston, said first mentioned ends being movable apart against their tension for release from said cartridge at said points.

6. In combination, a dental matrix having a filling tube projecting therefrom, a cartridge containing a supply of setting plastic filling material supported on said matrix and connected with said tube for discharge of said filling material through the latter, said cartridge being sufficiently small and light and to be capable of being supported by said matrix and the tooth to be filled independently of manual or other support when said matrix is secured to said tooth, means carried by said cartridge for yieldably urging said supply of plastic material therefrom and through said tube for ejection into the cavity adapted to be covered by said matrix, said means including a spring and a member for releasably holding said spring under tension against said supply of plastic.
